UNITED STATES PATENT OFFICE.

THOMAS GUNNING, OF PITTSBURG, PENNSYLVANIA.

FEED-WATER HEATER AND PURIFIER.

SPECIFICATION forming part of Letters Patent No. 693,268, dated February 11, 1902.

Application filed November 24, 1900. Renewed December 10, 1901. Serial No. 85,378. (No model.)

To all whom it may concern:

Be it known that I, THOMAS GUNNING, of Pittsburgh, in the county of Allegheny and State of Pennsylvania, have invented certain

5 new and useful Improvements in Feed-Water Heaters and Purifiers; and I do hereby declare the following to be a full, clear, and exact description of the invention, such as will enable others skilled in the art to which

10 it appertains to make and use the same.

This invention relates to feed-water heaters and purifiers, and is especially designed as an improvement on the means shown, described, and claimed in Letters Patent No.

15 657,238, issued to me September 4, 1900.

The object of the present invention is to provide improved means for preventing the lodgment of incrustation in the feed-water passage-ways within the superheating steam-

20 chamber.

In the before-noted patent I pointed out the advantages derived from passing the feed-water through a steam-chamber, whereby its temperature is raised to practically that with-

25 in the boiler, and showed the feed-water pipe passed tortuously through the steam-chamber. In my present invention the latter is provided with a series of horizontally-dis-

30 posed tubes mounted in headers, which tubes are surrounded by live steam, so that the wa-

35 ter passing through them will be brought up to boiler temperature, the water being introduced at one end of the chamber and dis-

charged at the other. To prevent the lod-

40 gement of incrustation or the deposit of any foreign substance on the interior of the tubes, I place within the latter a series of metallic bodies, such as chains, which, being incased by the tubes, will be of lower temperature

45 than the latter, and hence upon them the incrustation will form, it being well-known that such formation is always on a cooler portion of the surrounding casing. When this occurs to such an extent as to affect the temperature

45 of the discharged water, the chains are re-

50 moved from the tubes through hand-holes in one end of the steam-chamber and a new set substituted.

The invention will be hereinafter fully set

55 forth, and particularly pointed out in the

claims.

In the accompanying drawings, Figure 1 is

an end elevation with the superheating steam-chamber in section. Fig. 2 is a cross-sectional view on line 2-2, Fig. 1. Fig. 3 is an enlarged 55 view through a portion of one of the tubes.

Referring to the drawings, 1 designates a superheating steam-chamber, which is shown as being horizontally disposed above two boilers 2, forming part of a battery of boilers. 60 (Not shown.) At its top this chamber is connected by a valved pipe to an overhead steam-main 3, and at its bottom is connected by valved pipes 4 to the steam-spaces of the boilers 2. As pointed out in my before-men- 65 tioned patent, steam is supplied to the steam-chamber from the boilers 2 and steam-main leading from the battery of boilers, and any water of condensation within said chamber is allowed to drain through pipes 4 to the boil- 70 ers 2.

5 is a valved feed-water-supply pipe lead- 75 ing from a pump 6 and opening into chamber 1 near the end 7 thereof, which end is remov- ably secured to the flanged end of the cham- 80 ber and is equipped with a manhole 8. Within the chamber is a series of horizontally-dis- posed tubes 9, expanded at their ends in headers 10, secured by rivets or otherwise to the shell of the chamber. The water passes 85 through these tubes and out of the chamber adjacent to the end 12 through a pipe 13, by which it is conveyed first to a filter (shown at 14) and thence to a boiler through a pipe 15. The end 12 is also removably secured to 90 the flanged end of the chamber and is equipped with a plurality of hand-holes 16, normally closed. Within each of the tubes I place a metallic body, such as a chain 17. As pointed 95 out in my before-mentioned patent, the water forced from the feed-pump passes into the superheating steam-chamber, and by reason of the presence of live steam therein is heated or raised to boiler temperature, thereby precipitating all foreign substances contained in 100 the water and reducing the same to sludge. The chains within the tubes being of a lower temperature than that of the tubes them- selves will attract any sludge or incrustation-forming substances and prevent the same from depositing on the walls of the tubes. When it is found by means of a thermometer (not shown) that the water passing from the superheating steam-chamber falls below the

required temperature, it is indicative of the fact that incrustation is forming within the tubes. Thereupon the valves in pipes 4 are closed, as is also the valve in the pipe leading from the steam-main 3 and the valve in feed-water pipe 5. The covers of the hand-holes are removed and the several chains are withdrawn from the tubes of the steam-chamber and are either cleaned and then replaced or a new set of chains inserted, after which the hand-hole covers are restored. Any sediment within the end compartments of chamber 1 may be drawn off through the valved drain-pipes 19, projecting from the bottom of such chamber. In this way not only am I enabled to supply the battery of boilers with pure water heated to practically the temperature of the boilers, but I avoid all possibility of incrustation forming within the tubes in which the feed-water is heated in passing through the superheating steam-chamber.

Although I have specified removable chains as the medium employed for insuring the collection of incrustation-forming substances, yet it is obvious that the same results may be secured by inserting in each of the tubes any metallic article of such construction that it will extend throughout the length of each tube and which is capable of being readily withdrawn from or inserted in the same.

The ends of the steam-chamber being removable and one of them being equipped with a manhole, access may be readily had to the interior of said chamber in case repairs are found necessary or for the purpose of expanding or tightening the ends of the tubes.

The advantages of my invention are apparent to those skilled in the art.

I claim as my invention—

1. The combination with a superheating steam-chamber, and means for supplying live steam thereto, of a feed-water pipe entering the said chamber at one end and leading from the other end thereof, a series of water-tubes within said chamber, and a series of removable metallic bodies located in said tubes and designed to be removed therefrom when incrustation forms on such bodies, as set forth.

2. The combination with a superheating steam-chamber having normally closed openings in one of its ends, and means for supplying live steam to such chamber, of a feed-water pipe entering the said chamber at one end and leading from the other end thereof, a series of water-tubes within said chamber, and a series of removable metallic bodies located in such tubes, said bodies being designed to be removed through said openings when incrustation forms thereon, as set forth.

3. The combination with a superheating steam-chamber having normally closed openings in one of its ends, headers in said chamber, and water-tubes supported by said headers, of a feed-water pipe entering said chamber at one end, a second pipe leading from the other end of said chamber, and a series of removable metallic bodies located in said tubes and designed to be removed therefrom when incrustation forms thereon, as set forth.

4. The combination with a boiler or boilers, and an overhead steam-main, of a steam-chamber horizontally disposed above said boiler or boilers and intermediate of the latter and said main, pipes connecting said steam-chamber with said boiler or boilers and the steam-main, a feed-water pipe extending into said steam-chamber at one end thereof, headers in said chamber, water-tubes mounted in said headers, and a series of removable metallic bodies located in said tubes and designed to be removed therefrom when incrustation forms on them, as set forth.

In testimony whereof I have signed this specification in the presence of two subscribing witnesses.

THOMAS GUNNING.
